DESIGN FOR A SANDAL OR SIMILAR ARTICLE

Tycho Buek, Jr., Philadelphia, Pa.

Application March 20, 1934, Serial No. 51,109

Term of patent 3½ years

To all whom it may concern:

Be it known that I, TYCHO BUEK, JR., a citizen of the United States, residing at Philadelphia, in the county of Philadelphia and State of Pennsylvania, have invented a new, original, and ornamental Design for a Sandal or Similar Article, of which the following is a specification, reference being had to the accompanying drawing, forming a part thereof.

Fig. 1 is a front perspective view of a sandal or similar article embodying my new design; and
Fig. 2 is a top plan view thereof.

I claim:

The ornamental design for a sandal or similar article, as shown.

TYCHO BUEK, JR.
